ELECTRODE HOUSING GLASS

Joseph Wechsler, Long Beach, N. Y.

Application April 28, 1953, Serial No. 24,711

Term of patent 14 years

(Cl. D26—1)

To all whom it may concern:

Be it known that I, Joseph Wechsler, a citizen of the United States, residing at Long Beach, Nassau county, New York, have invented a new, original, and ornamental Design for an Electrode Housing Glass, of which the following is a specification, reference being had to the accompanying drawings, forming a part thereof.

Fig. 1 is an elevational view of an electrode housing glass embodying my new design;

Fig. 2 is a further elevational view thereof; and

Fig. 3 is a section through the housing taken on the line 3—3 of Fig. 2.

I claim:

The ornamental design for an electrode housing glass, as shown.
